UNITED STATES PATENT OFFICE.

FRED JOSEPH MOSER, OF KANE, PENNSYLVANIA.

ANCHOR FOR TUBINGS FOR GAS-WELLS.

1,150,875.

Specification of Letters Patent. Patented Aug. 24, 1915.

Application filed August 21, 1914. Serial No. 857,866.

To all whom it may concern:

Be it known that I, FRED J. MOSER, a citizen of the United States, residing at Kane, in the county of McKean and State of Pennsylvania, have invented new and useful Improvements in Anchors for Tubings for Gas-Wells, of which the following is a specification.

This invention relates to improvements in anchors for tubings for gas wells and consists in certain improvements in the construction thereof as will be hereinafter fully described and pointed out in the claims.

In high pressure wells, it is necessary to anchor the tubing. At the same time it is desirable to connect the tubing which comes from the well in a vertical direction so that the gas passages may be extended laterally from the tubing. This has been accomplished heretofore by arranging a clamp around the tubing and then connecting the clamp with the casing head or with a clamp on the casing head.

In the present invention I provide a connecting device for the top of the tubing with the anchor devices thus making a positive anchor for the tubing which taken in connection with the connecting device makes a cheaper and more effective construction.

The invention is illustrated in the accompanying drawings as follows:—

Figure 1 shows a perspective view of the anchor T. Fig. 2 a section on the lines 2—2 in Figs. 3 and 4. Fig. 3 an elevation of a casing head with an anchor T on the tubing extending from the head, the anchor T being secured by a casing clamp. Fig. 4 a similar view of a casing head wherein the anchor T is connected directly to the head.

1 marks the casing, 2 the tubing, 3 the casing head, 4 the stuffing box on the casing head through which the tubing extends and 5 a bottom connection in the anchor T for the tubing. The anchor T also has a cross connection 6 extending at right angles to the connection 5. Preferably there is a cross connection 6 at each side of the fitting as shown. A horizontal piping leads from the connection 6. Wings 7 extend outwardly from the connections 5 and 6, the wings being formed integrally with said connections. These wings have the perforations 7a. Anchor bolts 8 extend through these perforations and through the ears 9 on the clamp 10, the clamp 10 extending around the casing under the head 3. The wings extend lat-

erally beyond the periphery of the casing so that the bolts 8 may be parallel to the axis of the tubing. In this way a straight pull may be had on the bolts and the perforations in the wings and in the clamp may be vertical. This direction of the perforations simplifies the manufacture. If desired the connection may be arranged vertically extending from the top of the anchor T. A small connection 11 is shown on which is placed a pressure gage 12.

In Fig. 4 the construction is similar except that in place of the clamp 10, the ears 13 are formed directly on the head and the anchor bolts 8 extend through these ears.

The advantage of this anchor T, over the usual method of making the connections to the top of gas wells, such as bolting two-part clamps to the well tube 2 for anchoring the tubing and attaching the various fittings for the gages and gas outlets, is that it dispenses with the clamps and all of the fittings and forms a complete top connection for the well wherein provision is made for all of the requirements. It is a permanent fixture and can be furnished at less expense and placed on the well in less time than the usual clamps and fittings and it avoids the use of the customary two-part clamp that is fastened together on the well tube 2 with small bolts that have been known to fail.

The design of the anchor T, may be varied to some other form of pipe fittings having the wings for anchoring the tubing or casing in the well and I do not limit myself to the exact construction shown in the drawings.

What I claim as new is:—

1. In an anchor for tubings for gas wells, the combination of an anchor T, formed with a connection for the tubing, a cross connection, and anchor wings extending from the T; a casing; anchor bolts extending from the wings; and means for connecting the anchor bolts with the casing.
2. In an anchor for tubings for gas wells, the combination of an anchor T, formed with a connection for the tubing, a cross connection, and anchor wings extending from the T, and having vertical perforations therein; a casing; anchor bolts extending through said perforations; and means for connecting the anchor bolts with the casing.
3. An anchor T, for anchors for tubings for gas wells formed with a connection for

the tubing; a cross connection; and anchor wings extending from the T.

4. An anchor T, for anchors for tubings for gas wells formed with a connection for the tubing; a cross connection; anchor wings extending from the T; and a vertical connection leading from the top of the anchor T.

5. In an anchor for tubings for gas wells, the combination of a casing; an anchor fitting having a connection for the tubing; wings extending from the fitting laterally

beyond the outer periphery of the casing; and means acting on the wings for securing the fitting to the casing.

In testimony whereof, I have hereunto set my hand in the presence of two subscribing witnesses.

FRED JOSEPH MOSER.
